ELECTRIC SWITCH

Winfield A. Atwood, Yeadon, Pa., assignor to General Electric Company, a corporation of New York

Application April 24, 1942, Serial No. 446,296

17 Claims. (Cl. 200—89)

My invention relates to improvements in electric switches and more particularly high speed circuit breakers and especially circuit breakers for interrupting a direct or rectified alternating current circuit, whose current is increasing at a high rate, before the magnitude of the current can attain dangerous values.

Probably the greatest trouble experienced in the operation of mercury arc rectifiers arises from abnormal operating conditions such as an arc-back occasioned by reverse current flow from cathode to anode or by the striking of an arc discharge between anodes. The reversal of current flow establishes a short circuit which is fed not only by the other rectifying paths of the particular rectifier, but also by all the rectifiers operating in parallel with this rectifier. The rate of increase of current in this short circuit path is so high, particularly in large installations, that currents dangerous to equipment and personnel and destructive of service continuity are quickly reached. There have been observed rates of increase of current of over six million amperes a second for a single rectifier and over eleven million amperes a second where several are operated in parallel. It is, therefore, imperative to interrupt this short circuit current very quickly if the current at interruption is not to exceed a safe value and interruption of service is to be prevented. In short, the problem is to interrupt the circuit of the faulty anode so quickly as to limit the resulting current to a safe value. Moreover, this must be accomplished with apparatus which is not only dependable, but also economically feasible. Also, in the starting operation of mercury arc rectifiers, either initially or after a shutdown, it is customary to degas or bake out the rectifier for a period of time. During this period, safety to equipment and personnel requires that the means used to interrupt the anode circuit be positively maintained in the open circuit position.

One object of my invention is to provide an improved circuit breaker, the inertia of the movable parts of which is reduced to a minimum consistent with the required current carrying and interrupting capacity, and the arrangement of the parts of which is such as to facilitate a quick circuit opening operation. Another object of my invention is to provide an improved circuit breaker mechanism such that any one or more of a group of poles can be operated to the circuit closing position either manually or by a single motive power means without interfering with the closed poles and such that each pole is trip-free and independent of the others as far as interruption is concerned. Still another object of my invention is to provide a circuit breaker mechanism which can be operated by suitable motive power means or manually, as de-

sired, and yet readily placed in a condition positively to prevent the circuit closing operation. A further object of my invention is to provide an improved circuit breaker which will open so rapidly that it will limit and interrupt a current flowing through its closed contacts at a high rate of increase and in a predetermined direction before the magnitude of the current attains an unsafe value. A still further object of my invention is to provide an improved high current capacity circuit breaker having a simple but sturdy structure, capable of severe duty and yet economically feasible from the standpoint of installation, operation, and maintenance. These and other objects of my invention will herein-after appear in more detail.

In accordance with my invention, I reduce the weight of the moving parts of the circuit breaker structure and the friction between them to a minimum so as to obtain the quickest opening consistent with the necessary current carrying and interrupting capacity. Also, in accordance with my invention, I provide a latched closed type of circuit breaker mechanism embodying the minimum number of operating parts, which are so arranged as to permit a quick opening movement of the circuit breaker contacts upon release of the latch. Further in accordance with my invention, I provide a high speed trip mechanism which is normally electromagnetically held against a strong bias, the effect of which is immediately available for tripping under predetermined conditions of current flow through the circuit breaker contacts. Likewise, in accordance with my invention, I provide means operative during the opening movement of the circuit breaker to restore the latching mechanism to the holding position against its bias and to maintain it in the holding position as long as the circuit breaker is open and also while the circuit breaker is closed and providing the direction of current flow through its contacts is normal. Also, in accordance with my invention, I provide a circuit breaker structure such that in a grouping of two or more units or poles, any one or more of the poles can be closed independently of the others by a simple manual or motive power device with each pole free to open at any time independently of any of the others.

My invention will be better understood from the following description when considered in connection with the accompanying two sheets of drawings, and its scope will be pointed out in the appended claims.

In the accompanying two sheets of drawings, Fig. 1 is a vertical side elevation, partly broken away and partly in section of a circuit breaker embodying my invention; Fig. 2 is a fragmentary view illustrating certain of the parts at the instant of tripping. Fig. 3 is a partial view similar

to Fig. 1 showing an intermediate position of the parts during the circuit opening movement thereof; Fig. 4 is a view similar to Fig. 3 showing the circuit breaker parts in the full open position and ready to start the closing operation; Fig. 5 is a view similar to Figs. 3 and 4 illustrating the closing operation partially completed; Fig. 6 is a diagram illustrating how certain of the parts are arranged to maintain the breaker in the closed position; Fig. 7 is a part sectional view on the line 7—7 of Fig. 1 with one part reversed in position; Fig. 8 is a fragmentary view of a modification of the means used to hold the circuit breaker in the closed position; and Fig. 9 is an elevation to a larger scale of a contact mounting detail.

In the illustrated embodiment of my invention, a base or panel 10 of suitable insulating material has suitably secured thereto spaced lower and upper contact studs 11 and 12, respectively, which are provided with terminals 13 and 14, respectively. The stud 11 comprises a stationary contact block 15 having a curved contacting surface 16, which is preferably cylindrical for reasons presently to appear. The stud 12 comprises a contact block 17 in which is supported a plurality of relatively stationary contacts 18, only one of which appears in the drawings. Each of such contacts 18 is arranged for high pressure line contact with the stud block 17. For this purpose, each contact 18 is mounted with its upper end fitting somewhat loosely in a cylindrical recess 19 in the stud block 17. As shown more clearly in Figs. 1 and 9, the mounting for each contact 18 includes a headed screw 20 which is supported in an opening in the stud 12 and screwed into the block 17. In order to maintain a sharp current loop at the contact recess 19, the head of the screw 20 is centered in the opening of the stud 12 by suitable insulating means such as a bushing 20' to prevent the passage of current from the block 17 through the screw 20 and the spring 21 to the stud 12. The screw 20 carries a backing spring 21, the bias of which holds the upper end 22 of the contact 18 forward against the face of the recess 19 in line-to-line contact. For better contact action, the upper end of the contact 18 and the surface of the recess 19 against which it bears may be silver faced. Likewise, the lower end of the contact 18 may be provided with a silver contact piece 23.

For completing a circuit through the circuit breaker, there is provided a contact 24, which is fulcrumed on the curved contacting surface 16 of the stationary contact 15 for movement into engagement with the relatively stationary contact 18 by a mechanism constructed in accordance with my invention so as to insure high speed circuit opening action. In the arrangement illustrated, the lower end of the contact 24 is provided with a plane contact surface 25 which fulcrums on the cylindrical contact surface 16 of the contact block 15. Both of the contact surfaces 16 and 25 are preferably silver faced for better contact action. At an intermediate point in its length, the movable contact 24 is provided with a silver contact portion 26, which is arranged to engage the silver portion 23 on each of the contacts 18. The contacts 18 are spaced slightly by separators 27 in order that each may be free to move independently of the others under the magnetic attracting forces between them due to the currents flowing through them in the same direction and thus come to a better bearing in the contact recess 19 and against the contact face 26 of the movable contact 24. The separators 27 are preferably not of magnetic material but suit-

able insulating material may be used. In addition to the primary stationary contacts 18 there is also provided a secondary or arcing stationary contact 28 whose upper end is mounted in a cylindrical recess 29 in an arcing contact block 30 separated from the contact block 17 by suitable insulation. Like the primary stationary contacts 18, the secondary stationary contact 28 is biased forward to engage the arcing contact block 30 in line-to-line contact. For this purpose, there is provided suitable means, such as one or more backing springs 31, which are mounted in holes in the stud 12. The backing springs 31 do not engage the contact 28 directly but are spaced therefrom by insulating rods 32. The lower end of the secondary stationary contact 28 and the upper end of the movable contact 24 are provided with suitable contact portions 33.

For arc extinguishing purposes, the arcing contact block 30 is provided with an arcing horn extension 34 and is, also, connected to the stud 12 through a blowout coil 35. For carrying the end of the arc off from the contact portion 33 of the movable contact 24, there is provided a blowout coil 36 with suitable core, the coil 36 being connected between an arcing horn 37 and the lower stud 11 of the circuit breaker. The connection to the lower stud is broken away in Fig. 1 for the purpose of clearness of illustration of the breaker mechanism. The arc extinguishing structure further includes pole pieces (not shown) for the core in coil 35 and two enclosing barriers 38, only one of which appears in the drawing.

In order that the plane face 25 of the movable bridging contact 24 may pivot on the cylindrical face 16 of the contact block 15, I mount the contact 24 on suitable supporting means, such as a cradle, pivoted to rotate about an axis which is substantially in line with the element of the cylindrical surface 16 about which the contact pivots as a line contact. In other words, the construction is such that the pivotal axes of the contact 24 and the cradle are as nearly coincident as possible in order to reduce the sliding between and consequent wear of the contact surfaces 16 and 25 to a minimum. As shown, this cradle comprises two spaced side members 39, only one of which appears in the drawing. Each of these is supported on a pivot 40 mounted in the side 41 of the circuit breaker frame adjacent the side member of the cradle. At the upper end, the side members 39 are joined by a pivot 42, which passes through the contact 24 and leaves this contact free to be biased against the contact surface 16 and for high speed of opening operation. It is here noted that in the circuit closed position of the contact structure described, the magnetic loop expansion effect produced by any current through the circuit breaker increases the pressure between the contacts as long as the cradle 39 is maintained in the circuit closing position and, consequently, tends to accelerate contact separation when the cradle is free to rotate clockwise about its pivot 40.

In order to move the cradle 39 into and maintain it in the circuit closing position and yet have it quickly freed for high speed interruption, I provide a movable abutment 43, releasable means comprising a latch 44 pivoted in the frame 41 at 44' for holding the abutment 43 in a predetermined position, and actuating means comprising a member 45 movable on the abutment 43 and between the abutment and a member 46 movable with the bridging contact 24, for example, pivoted on the cradle 39. In order to minimize fric-

tion and facilitate high speed operation, the members 45 and 46 are preferably rollers, as shown. The abutment 43 is mounted on a pivot 47 extending between the sides 41 of the circuit breaker frame. In order to obtain the counterclockwise movement of the cradle 39 necessary to bring the contact 24 into the normal current conducting position, the abutment is provided with a suitably shaped cam face 48, which is traversed by the roller 45. The roller 45 is thus movable between a surface 46 movable with and relatively to the bridging contact and the opposing cam surface 48 of the movable abutment and on this cam surface. For actuating the roller 45, I provide an operating member 49, which, as shown, is mounted on the pivot 47 and is connected to the roller 45 through one or more operating links 50. These links are pivoted to the operating member 49 at 51 and to the roller 45 at 52. The operating member comprises two side pieces 49 and a cross connection 53, which in the closed position of the circuit breaker abuts the frame 41 at 54, as shown in Fig. 1. In order to maintain the circuit breaker in this closed position as long as the abutment 43 is maintained in the latched position, the parts are so proportioned and arranged that in the closed position of the circuit breaker, the direction of pressure on the roller 45 tends to force this roller to the right on the cam surface 48. This will be more clearly understood from a consideration of Fig. 6 wherein the direction A of the pressure tending to open the circuit breaker passes through the centers of curvature of the rollers 45 and 46 and intersects the cam surface 48 at a point just sufficiently to the right of the line B through the centers of curvature of the roller 45 and the cam surface 48 to provide the necessary holding bias.

For releasing the latch 44 so as to effect the opening of the circuit breaker, I provide electromagnetic means responsive to a predetermined abnormal condition of the circuit controlled by the circuit breaker. The particular means illustrated is responsive to a predetermined direction of flow of direct current. As shown, this means comprises two U-shaped cores 55 and 56 of suitable magnetic material arranged substantially perpendicularly to each other and having two common polar extensions 57, only one of which appears in the drawings, with an air gap arranged to be bridged by an armature 58. The core 55 is secured to the frame 41 so as to embrace the stud 11 and is accordingly energized responsively to the magnitude and direction of the current flowing through the circuit breaker. The core 55 is energized by polarizing windings 59, one on each leg of the magnet and energized preferably from a source of direct potential although rectified alternating current may be used. The flux of these polarizing windings alone is sufficient to maintain the armature 58 in the attracted position against the bias of a latch actuating spring 60, which pushes against the tail of the latch 44 through a collared rod 61 passing through the armature 58. A turned down portion of the rod 61 passes through the armature 58, the shoulder on the rod where the diameter is reduced being employed to move the armature 58 away from the magnet pole faces because of the bias of the spring 60 on the occasions of predetermined current conditions in the breaker. The magnetic structure and arrangement is such that when current flows through the circuit breaker in a predetermined direction the flux

due to the current is additive in its effect to the armature holding effect of the flux due to the windings 59. However, when current flows through the circuit breaker in a direction opposite to said predetermined direction, the two fluxes not only are subtractive in their resultant holding effect, but also are so shifted that the armature 58 is quickly released to trip the latch 44 under the action of the spring 60. The bias of the spring may be controlled by a nut 62 threaded on a spring support 63, which may also serve to secure the removable bottom of the U-shaped magnetic structure to the stud 11, as shown. The weight of the armature 58 and the movable parts directly associated therewith is reduced to a minimum in order to expedite the circuit opening action of the circuit breaker.

For resetting or returning the armature 58 to the attracted position during the opening of the circuit breaker, I provide means responsive to the movement of the abutment 43. As shown, this means comprises a link 64 pivoted at 65 to the abutment 43 and to the latch 44 at 66 through a slotted opening 67, the purpose of which is to allow a desired counterclockwise movement of the abutment before resetting the armature. In order to prevent undue shock to the armature 58 during the resetting movement, I provide a shock absorbing spring 68 around the stem of the rod 61 on the side of the armature away from the polar extensions 57. The plug 69, screwed into the frame, provides a shoulder stop for armature 58 so that the latter may not compress the spring 68 to its solid height as the armature moves and thereby strip the collar 70 secured to the rod 61 therefrom. For resetting the abutment 43 and the latch 44 to the sustaining position, I provide abutment return springs 71 and a latch return spring 72. The former is secured to the abutment pivot 47 and to the frame 41 and tends to turn the abutment clockwise about its pivot 47. The latch return spring 72 is connected between the latch 44 and the frame 41 and tends to turn the latch clockwise about its pivot 44'.

For effecting a quick movement of the contact 24 to the circuit opening position, exerting pressure between the contact surfaces 16 and 25 at all times, and also recompressing the tripping spring 60, I provide suitable energy storing means, such as biasing springs 73, only one of which appears in the drawings. These springs are positioned outside of the cradle 39. In order to have them suitably stressed during the closing movement of the breaker, they are connected between a stud 74 supported in the sides of the frame 41 and a rod 75 fixed in the movable contact 24 but extending through slotted openings, not shown, in the cradle sides 39 so as to permit a predetermined movement of the contact 24 relatively to the cradle 39. For exerting pressure between the contact surfaces 16 and 25 at all times and also returning the operating member 49 and the parts connected thereto to the position shown in Fig. 4, I provide suitable energy storing means, such as a biasing spring 76. In order to have this spring suitably stressed during the closing movement of the circuit breaker, it is connected between the pivot 51 and a rod 76' fixed in the contact 24 which is provided with a hollow portion for receiving the end of the spring.

Since mercury arc rectifiers usually have six anode circuits and sometimes more, I provide an arrangement whereby a plurality of single-

pole circuit breakers in the open circuit position can be closed simultaneously, and also any one or more poles can open and can be closed without interfering with the poles that are closed whereby to avoid unnecessary interruptions in sound anode circuits. For this purpose, I provide each pole with an actuating lever 77 pivoted at 47 and then interconnect these levers by a common actuating means comprising a crossbar 78. As shown, the actuating lever 77 is U-shaped with a cross piece 73 having a projection 80 arranged to abut the cross piece 53 of the operating crank 49. In order to insure that each pole will be positively closed, I adjustably position the projection 80 so as to take care of manufacturing tolerances and variations in lost motion whereby to insure the desired closing action of any one or more poles even though the others are closed. The projection 80 is so adjusted that a predetermined clockwise movement of the actuating lever 77 will impart sufficient clockwise movement to the operating crank 49 to effect the holding bias of the rollers, as explained in connection with Fig. 6. This, in general, will cause the operating crank 49 to settle with its cross piece 53 abutting the frame 41 at 54 with some clearance between the projection 80 and the cross piece 53. However, it is possible that the final holding biased position of the crank 49 may be reached at the end of the clockwise movement of the actuating lever 77. In this case, the projection 80 may continue to abut the operating crank cross piece 53.

For actuating the crossbar 78 to close the circuit breaker pole units, I provide a motive power mechanism, which is also adapted to manual operation. As shown, this mechanism comprises a motor-driven mechanism of the type disclosed in United States Letters Patent 2,034,145, issued March 17, 1936, and assigned to the assignee of this invention. This mechanism comprises an electric motor 81 provided with a hand wheel 82 mounted on its shaft and arranged to drive through a gear mechanism, not shown, a cam 83 of suitable contour. The motion of this cam is imparted to the crossbar 78 through a crank 84 pivoted at 85 in the mechanism frame 86 and connected to the crossbar through a connecting rod 87 at pivotal points 88 and 89, the latter being in bracket pieces 90 secured to the crossbar 78. The crank 84 is provided with a socket portion 84' for the reception of a suitable lever or rod 92 whereby the closing operation may be manually performed. For raising the crank 84, the connecting rod 87 and the actuating levers 77 to a position which permits resetting the operating crank 49 and parts connected thereto in order to close the circuit breaker, I provide retrieving or raising means, such as one or more springs 93 connected between the motor mechanism frame at 84 and the crank 84 at 95 in such a way as to exert an upward thrust on the connecting rod 87 when the cam 83 is turned counterclockwise sufficiently to permit counterclockwise movement of the crank 84.

In order to prevent a closing operation of the circuit breaker when, for example, it is desired to work on the structure thereof or apparatus whose circuits are controlled by the circuit breaker, I provide means for preventing movement of the crossbar 78 either by the motor 81 or manually. As shown in Figs. 1 and 7, this means comprises a control member 96, which can be positioned in the side of the operating mechanism frame 86 in two ways, one of which, as

shown in Fig. 1, will permit the closing operation, and the other of which, as shown in Fig. 7, will prevent the closing operation. For the latter purpose, one end of the control member 96 has a projection 97, which when the member is screwed into the frame 86, preferably above the projection 98, as shown in Fig. 7, projects into the path of movement of a lug 98 on the mechanism crank 84 so as to prevent counterclockwise movement thereof from the position shown in Fig. 1. As the springs 93 cannot lift the crank 84 and the parts attached thereto from the normal down position with the projection 97 assembled as described, it will be impossible to close the circuit breaker, although the motor 81 itself may be run through its operating cycle. If the control member is screwed into the frame with the projection 97 inside, as shown in Fig. 7, while the mechanism crank 84 is in the upper position, that is, with the lug 98 above the projection 97, then the crank 84 cannot be turned clockwise sufficiently to close the circuit breaker.

Assuming the circuit breaker closed with the parts positioned as shown in Fig. 1 and current flowing through the circuit breaker in the direction which causes the flux of the electromagnet 55 to assist the flux of the polarizing electromagnet 56 to hold the armature 58 in the attracted position against the bias of the tripping spring 60, then, if the direction of the current flowing through the circuit breaker is reversed as in the case of an arc-back in the anode circuit of a mercury arc rectifier, the armature is quickly released because of flux opposition and shift in the common magnetic path including the air gap bridged by the armature. The effect of the strong tripping spring 60 is to move the latch 44 forcibly counterclockwise about its pivot 44' thus releasing the abutment 43, and momentarily the parts assume the position shown in Fig. 2. Since there is no longer any support for the left-hand or free end of the abutment 43, the tension of the opening springs 76 and to a certain extent, the springs 78 and the contact springs 21 and 31 together with the weight of the parts bearing on the abutment 43 forces this member to turn in a counterclockwise direction about its pivot 47 whereby quickly to effect the opening of the circuit breaker with the parts positioned as shown in Fig. 3. In this position, the bias on the roller 45, which was away from the panel 10, that is in a direction to hold the circuit breaker closed, is now directed toward the panel. If, after the opening of the circuit breaker, manual or automatic means are utilized to energize the circuit of the motor 81 or the hand wheel 82 is turned sufficiently in a direction to rotate the cam 83 counterclockwise, as viewed in Fig. 1, then the crank 84 will be free to rotate counterclockwise about its pivot 85 under the tension of the retrieving springs 93, thus raising the crossbar 80 to the position shown in Fig. 4 with the actuating lever 77 turning counterclockwise about its pivot 47. While this motion is going on, the remaining tension on the spring 76 turns the operating crank 49 counterclockwise about its pivot 47 so that the roller 45 under its bias toward the panel moves to its lowest position on the cam surface 48 of the abutment 43. During this movement, the abutment 43 and its sustaining latch 44 are returned to the latching position under the biasing actions of their respective springs 74 and 72. In other words, the circuit breaker mechanism is reset as shown in Fig. 4 and ready for the actual closing movement to the

position shown in Fig. 1. As the cam 83 continues to turn counterclockwise under the action of the motor 81 or rotation of the hand wheel 82, the crank 84 is turned clockwise about its pivot 85 and through the connecting rod 87, turns the actuating crank 77 clockwise about its pivot 47. With this movement of the actuating crank, the projection 80 engages the transverse portion 53 of the operating crank 49, as shown in Fig. 5, to rotate this member clockwise about its pivot 47. As this motion takes place, the roller 45 travels along the cam surface 48 in contact with the roller 46 to force the cradle 39 to turn counterclockwise about its pivot 40 and thereby to effect the engagement of the contact 24 with the contacts 18 and 28. During this movement, the springs 73 and 76 are stressed in preparation for the next opening action and also to maintain the desired contact pressure between the contact surfaces 16 and 25. The parts are then again in the circuit closing position, as shown in Fig. 1. When a plurality of circuit breaker poles are under the control of the crossbar 78, each pole that opens during the movement of the crossbar will be closed by the downward movement thereof provided the mechanism of the opened pole can move from the position shown in Fig. 3 to the reset position shown in Fig. 4 before the movement of the crossbar has proceeded so far as to prevent such resetting action. If with the breaker open at any time it is desired to prevent a closing operation, then the control member 96 may be reversed from the position shown in Fig. 1 to the position shown in Fig. 7 so that the projection 97 of this member is above the lug 98 on the crank 84.

Instead of holding the contact 24 in the circuit closing position by the roller biasing arrangement described in connection with Figs. 1 and 6, I may so arrange the parts, as shown in Fig. 8, that the line of pressure A' tending to open the circuit breaker passes through the centers of curvature of the rollers 45 and 46 and intersects the cam surface 48 at a point just sufficiently to the left of the line B' through the centers of curvature of the roller 45 and the cam surface 48 to bias the contact 24 to the circuit opening position. Then in order to hold the contact 24 in the circuit closing position, I provide a latching member 99 pivoted on the frame 41 at 100 and arranged to engage a suitably shaped latching edge on the cross member 53' of the operating crank 49. The latch 99 is biased for clockwise movement about its pivot 100 to the latching position shown by suitable means, such as a spring 101. The clockwise movement of the latch 99 is limited by having the tail of the latch about the frame 41, as shown. In this modification of my invention, the latch 99 is released during the counterclockwise movement of the abutment 43, the tail portion 43' of which strikes the tail portion of the latch 99 to free it from the operating crank 49. Also, in this modification of my invention, I have shown a slightly different biasing means for resetting the latch 44 and the abutment 43. As shown, this means comprises an abutment retrieving spring 102, the right-hand end of which is connected to the abutment at 103 and the left-hand end of which is connected to the frame 41. The resetting means also includes a spring 104 which is connected between the abutment 43 at 103 and the latch 44 at 105. The operation of this modification of my invention will be obvious from the foregoing taken in connection with the descrip-

tion of the embodiment of my invention shown in Fig. 1.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

10. 1. An electric switch comprising a pivotally supported contact, a cooperating contact, and means for moving said pivotally supported contact into engagement with said cooperating contact comprising a first roller mounted to move with said pivotally supported contact, a member having a surface of a predetermined contour, and a second roller movable over said surface and between the surface and said first roller to effect the circuit closing movement of said pivotally supported contact.
15. 2. An electric switch comprising a relatively stationary contact, a pivotally supported contact movable into engagement with said stationary contact, a first roller movable with said pivotally supported contact, a movable abutment, means for holding said abutment in a predetermined position, and actuating means for moving the pivotally supported contact into engagement with the stationary contact when the abutment is in said predetermined position comprising a second roller movable on said abutment and between the abutment and said first roller.
20. 3. An electric switch comprising a pivotally supported contact, a cooperating contact, and means for moving said pivotally supported contact into engagement with said cooperating contact comprising a first roller mounted to move with said pivotally supported contact, an abutment having a surface of a predetermined contour, means for holding said abutment in a predetermined position relatively to the circuit closing position of said pivotally supported contact, a second roller movable in one direction over said surface and between the surface and said first roller to effect the circuit closing movement of said pivotally supported contact when the abutment is held in said predetermined position, and means adapted to be operated to effect the movement of said second roller in said direction.
25. 4. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
30. 5. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
35. 6. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
40. 7. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
45. 8. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
50. 9. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
55. 10. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
60. 11. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
65. 12. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
70. 13. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.
75. 14. An electric switch comprising a pivotally supported contact, a cooperating contact, and means for moving said pivotally supported contact into circuit closing engagement with said cooperating contact comprising a first roller mounted to move with said pivotally supported contact, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller.

ment in a predetermined position, a second roller movable in one direction over the surface of said abutment between the abutment and said first roller to effect the circuit closing engagement of said contacts when the abutment is held in said predetermined position, and means adapted to be operated to effect the movement of said second roller, said second roller being positioned relatively to said first roller and the surface of said abutment when said contacts are in normal current conducting engagement to maintain said engagement while said abutment is held in said predetermined position.

6. An electric switch comprising two relatively stationary contacts, a bridging contact fulcrumed on one of said stationary contacts for movement into engagement with the other stationary contact, a first roller mounted to move with said bridging contact, a movable abutment, means for holding said abutment in a predetermined position, and actuating means for moving the bridging contact into engagement with said other stationary contact when the abutment is in said predetermined position comprising a second roller movable on said abutment and between the abutment and said first roller.

7. An electric switch comprising two relatively stationary contacts, a bridging contact fulcrumed on one of said stationary contacts for movement into engagement with the other stationary contact, a surface movable with and relatively to said bridging contact, a movable abutment having a surface opposed to said movable surface, releasable means for holding said abutment in a predetermined position, and actuating means for moving the bridging contact into engagement with said other stationary contact when the abutment is in said predetermined position comprising a member movable on said abutment surface and between the abutment surface and said movable surface, said member being positioned when the bridging contact is in normal current conducting engagement with the stationary contacts to maintain said engagement while said abutment is held in said predetermined position.

8. An electric switch comprising two relatively stationary contacts, a bridging contact fulcrumed on one of said stationary contacts for movement into engagement with the other stationary contact, a surface movable with and relatively to said bridging contact, a movable abutment having a surface opposed to said movable surface, releasable means for holding said abutment in a predetermined position, actuating means for moving the bridging contact into engagement with said other stationary contact when the abutment is in said predetermined position comprising a member movable on said abutment surface and between the abutment surface and said movable surface, said member being positioned when the bridging contact is in normal current conducting engagement with the stationary contacts to maintain said engagement while said abutment is held in said predetermined position, means in which energy is stored during the movement of the bridging contact into engagement with said other stationary contact for quickly effecting movement of the bridging contact away from said other stationary contact upon release of said holding means, and means for effecting the release of said holding means.

9. An electric switch comprising two relatively stationary contacts, a bridging contact fulcrumed on one of said stationary contacts for movement into engagement with the other stationary contact,

- tact, a surface movable with and relatively to said bridging contact, a movable abutment having a surface opposed to said movable surface, releasable means for holding said abutment in a predetermined position, actuating means for moving the bridging contact into engagement with said other stationary contact when the abutment is in said predetermined position comprising a member movable on said abutment surface and between the abutment surface and said movable surface, means for maintaining the bridging contact in normal current conducting engagement with the stationary contacts while said abutment is held in said predetermined position, means in which energy is stored during the movement of the bridging contact into engagement with said other stationary contact for quickly effecting movement of the bridging contact away from said other stationary contact upon release of said holding means, and means for effecting the release of said holding means.
10. An electric switch comprising two relatively stationary contacts, a bridging contact, means supporting said bridging contact in pivotal engagement on one of said stationary contacts and for movement into and from engagement with the other stationary contact, a pivotally mounted element having a cam surface of a predetermined contour, releasable means for holding said element in a predetermined position, a first roller mounted on said supporting means, actuating means comprising a second roller movable on said cam surface between the surface and said first roller and means adapted to be operated to move said second roller on said cam surface in a direction to effect engagement of said bridging contact and said other stationary contact when said element is in said predetermined position, means for maintaining said bridging contact in normal current conducting engagement with said stationary contacts while said element is held in said predetermined position, means in which energy is stored during the movement of the bridging contact into engagement with said other stationary contact for quickly effecting movement of the bridging contact away from said other stationary contact upon release of said holding means, and means energizable to effect the release of said holding means.
11. An electric switch comprising two relatively stationary contacts, a bridging contact, means supporting said bridging contact in pivotal engagement on one of said stationary contacts and for movement into and from engagement with the other stationary contact, a pivotally mounted element having a cam surface of a predetermined contour, releasable means for holding said element in a predetermined position, a first roller mounted on said supporting means, and actuating means comprising a second roller movable on said cam surface between the surface and said first roller and means adapted to be operated to move said second roller on said cam surface in a direction to effect engagement of said bridging contact and said other stationary contact when said element is in said predetermined position, the position of said rollers relatively to each other and to the cam surface of said element when the bridging contact is in normal current conducting engagement with both of the stationary contacts being such as to maintain such engagement while said element is held in said predetermined position.
12. An electric switch comprising two relatively stationary contacts, a bridging contact,

means supporting said bridging contact in pivotal engagement on one of said stationary contacts and for movement into and from engagement with the other stationary contact, a movable abutment, releasable means for holding said abutment in a predetermined position, a first roller mounted on said supporting means, and actuating means comprising a second roller movable on said abutment between the abutment and said first roller and means adapted to be operated to move said second roller on said abutment in a direction to effect engagement of said bridging contact and said other stationary contact when said abutment is in said predetermined position, the relative position of said rollers with respect to each other and said abutment being such as to maintain said bridging contact in normal current conducting engagement with said stationary contacts after movement to such engagement while said abutment is held in said predetermined position.

13. An electric switch comprising two relatively stationary contacts, a bridging contact, means supporting said bridging contact in pivotal engagement on one of said stationary contacts and for movement into and from engagement with the other stationary contact, a movable abutment, releasable means for holding said abutment in a predetermined position, a first roller mounted on said supporting means, actuating means comprising a second roller movable on said abutment between the abutment and said first roller and means adapted to be operated to move said second roller on said abutment in a direction to effect engagement of said bridging contact and said other stationary contact when said abutment is in said predetermined position, and means for maintaining said bridging contact in normal current conducting engagement with said stationary contacts while said abutment is held in said predetermined position.

14. An electric switch comprising a relatively stationary contact, a movable contact, means pivotally supporting said movable contact, a movable surface on said supporting means, a pivotally mounted element having a cam surface of a predetermined contour opposed to the movable surface on said supporting means, releasable means for holding said element in a predetermined position, actuating means for moving said pivotally mounted contact into engagement with said stationary contact when the element is in said predetermined position comprising a member movable along said cam surface and between the cam surface and said movable surface, said member being positioned when the pivotally mounted contact is in normal current conducting engagement with the stationary contact to maintain said engagement while said element is held in said predetermined position, means in which energy is stored during the movement of the pivotally mounted contact into engagement with the stationary contact for quickly effecting movement of the pivotally mounted contact away from the stationary contact upon release of said holding means, and means for effecting the release of said holding means.

15. An electric switch comprising a relatively stationary contact, a bridging contact, means pivotally supporting said bridging contact, a movable surface on said supporting means, a pivotally mounted element having a cam surface of a predetermined contour opposed to the movable surface on said supporting means, releasable means

- for holding said element in a predetermined position comprising an armature biased to the unattracted position and a holding winding for maintaining said armature in the attracted position against the bias thereof, actuating means for moving the bridging contact into engagement with said stationary contact when the element is in said predetermined position comprising a member movable along said cam surface and between the cam surface and said movable surface, said member being positioned when the bridging contact is in normal current conducting engagement with the stationary contact to maintain said engagement while said element is held in said predetermined position, means in which energy is stored during the movement of the bridging contact into engagement with the stationary contact for quickly effecting movement of the bridging contact away from the stationary contact upon release of said holding means, means for opposing the holding action of said holding winding to effect movement of said armature under its bias whereby to release said element from said predetermined position, means dependent on the movement of the element during the circuit opening movement of the bridging contact for returning said armature to the attracted position, and means for effecting the release of said holding means.
16. An electric switch comprising two relatively stationary contacts, a bridging contact, means supporting said bridging contact in pivotal engagement on one of said stationary contacts and for movement into and from engagement with the other stationary contact, pivotally mounted element having a cam surface of a predetermined contour, releasable means for holding said element in a predetermined position, a first roller mounted on said supporting means, actuating means comprising a second roller movable on said cam surface between the surface and said first roller and means adapted to be operated to move said second roller on said cam surface in a direction to effect engagement of said bridging contact and said other contact when said element is in said predetermined position, said second roller being positioned relatively to said first roller and said cam surface when the bridging contact is in normal current conducting engagement with said stationary contacts to maintain said engagement while said element is held in said predetermined position, means in which energy is stored during the movement of the bridging contact into engagement with said other stationary contact for quickly effecting movement of the bridging contact away from said other stationary contact upon release of said holding means, and means energizable to effect the release of said holding means.
17. An electric switch comprising a pivotally supported contact, a cooperating contact, a surface movable with and relatively to said cooperating contact, a movable abutment having a surface opposed to said movable surface, releasable means for holding said abutment in a predetermined position, and means for moving the pivotally supported contact into engagement with the cooperating contact when the abutment is in said predetermined position comprising a member movable on said abutment surface and between the abutment surface and said movable surface.

WINFIELD A. ATWOOD.
